UNITED STATES PATENT OFFICE

EDWARD ZUPNIK, OF WASHINGTON, DISTRICT OF COLUMBIA

DESIGN FOR A CELLOPHANE CONTAINER

Application filed June 9, 1931. Serial No. 40,134. Term of patent 3½ years.

To all whom it may concern:

Be it known that I, EDWARD ZUPNIK, a citizen of the United States, residing at Washington in the District of Columbia, have invented a new, original, and ornamental Design for a Cellophane Container, of which the following is a specification, reference being had to the accompanying drawings, forming part thereof.

I claim:

The ornamental design for a cellophane container substantially as shown.

EDWARD ZUPNIK.
